CLAIM

The ornamental design for a set of portable printer and docking station, as shown and described.

DESCRIPTION

FIG. 1 is an exploded perspective view of the set of portable printer and docking station showing our new design;

FIG. 2 is a perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom view thereof;

FIG. 9 is a perspective view of the portable printer of the set of portable printer and docking station;

FIG. 10 is a front view thereof;

FIG. 11 is a rear view thereof;

FIG. 12 is a left side view thereof;

FIG. 13 is a right side view thereof;

FIG. 14 is a top plan view thereof;

FIG. 15 is a bottom view thereof;

FIG. 16 is a perspective view of the docking station of the set of portable printer and docking station;

FIG. 17 is a front view thereof;

FIG. 18 is a rear view thereof;

FIG. 19 is a left side view thereof;

FIG. 20 is a right side view thereof;

FIG. 21 is a top plan view thereof; and,

FIG. 22 is a bottom view thereof.

(Continued)

The broken lines shown in the drawings depict portions of the set of portable printer and docking station that form no part of the claimed design.
